DESIGN FOR A BROOCH

George M. Carson, Providence, R. I.

Application March 26, 1940, Serial No. 91,246

Term of patent 3½ years

To all whom it may concern:

Be it known that I, George M. Carson, a citizen of the United States, residing at Providence, in the county of Providence and State of Rhode Island, have invented a new, original, and ornamental Design for a Brooch, of which the following is a specification, reference being had to the accompanying drawing, constituting a part thereof.

Fig. 1 is a front elevation of a brooch showing my new design;

Fig. 2 is a side elevation thereof;
Fig. 3 is a foreview thereof; and
Fig. 4 is a front elevation of the brooch in turned position.

I claim:

The ornamental design for a brooch, substantially as shown.

GEORGE M. CARSON.
